(57) **CLAIM**

The ornamental design for a milk bag adaptor as shown and described.

DESCRIPTION

FIG. 1 is a perspective view showing a milk bag adaptor according to my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the milk bag adaptor shown in broken lines are included for the purpose of illustrating unclaimed portions of the milk bag adaptor and form no part of the claimed design.
